UNITED STATES PATENT OFFICE

2,564,061

DAYLIGHT SUN ILLUMINATED CROSS
AND TOWER

Bert G. Goble, Tulsa, Okla.

Application January 31, 1946, Serial No. 644,543

2 Claims. (Cl. 20—1)

1

This invention relates to daylight sun illuminated cross and church tower, but may be used for other things such as memorial for soldiers, and the cross may be placed out on mountain-side or top to be seen from cities or by passersby. When the sun shines on this cross it reflects and gives the effect of large diamonds reflecting light.

The cross may be made up of truncated spheres or the like silvered on the inside of glass as a mirror, or may be metal with a reflecting surface of the desired curved surface to reflect sun or artificial light to the direction desired, and an object of the invention is the harnessing up of this reflected light to follow one looking to different positions or angles from the cross. Also a new and novel tower is provided for the support of the cross or crosses, with a symmetrical gradual tapered top with no noticeable offsets visible and which tapered top seems like part of the tower and gives the appearance of all being built to support the cross on its top.

The main object of this invention is to create a new style church tower running its pilaster columns clear to the top of the square or octagon without being tied together with a belt course, and making a top tying into and a part of the tops of said pilasters without the noticeable offsets in all old style architecture which architects have tried to eliminate the last thousand years, and this symmetrical tapered top is finished with a cross that the sun illuminates in daytime and can be illuminated by night by floodlighting. The four main piers or pilasters are distinctly separated in appearance their full lengths, especially at their tops where it has been customary to tie them together by a belt course. My design intentionally does just the opposite, separating these columns by setting the windows and their turnaways back from the face of the columns with no noticeable offsets on tapered top of pinnacles, accomplishing the idea lacking in all other towers.

One of the main objects of this invention is to form the top of a church tower that does not have noticeable offset but gradually tapers off to a peak.

Another object of this invention is to form the top of a church tower or other tower that blends into and onto the top of the main pilaster columns and seems part of them or with a similarity, giving the appearance of tying them all into one unit.

Another object of this invention is to make a church tower with many points pointing upward in the general direction of the cross on its top and

2

emphasizing the Gothic architecture by many vertical lines and few horizontal lines.

Another object of this invention is to build a church tower lacking carving but carrying dignity in its design and the general appearance of being all built to support a cross.

Another object of this invention is to make the top of a church tower with seven tiers of pinnacles representing the seven days of the week, 10 the seventh being the Lord's day on which the cross is placed.

With the above and other objects in view the invention consists in general of certain new and novel ideas and details of construction and combination of parts hereinafter fully described, illustrated in the accompanying drawings and claimed.

In the drawings:

Figure 1 is the top portion of a church tower 20 constructed in accordance with the present invention.

Figure 2 is an enlarged view of part of the cross on top of tower.

Figure 3 is a section of one of the truncated 25 spheres of the cross taken at line A—A in Figure 2.

Figure 4 is a cross sectional view taken at line B—B in Figure 2.

Figure 5 is a plan view of one of truncated 30 spheres making up the cross in Figure 2.

Figure 6 is a side view of one of the pliable washers placed over the pipe and between the truncated spheres.

Figure 7 is the edge view of washer shown in 35 Figure 6.

Figure 8 is side view of a reflector of a different shape.

Figure 9 is a fragmentary sectional view showing 40 the manner of mounting a sphere of a cross on a support.

Figure 10 is a side view of Figure 9 showing portion of the center of the reflector concaved to cause a different result in reflecting to that of the sphere shaped reflector and fastened to a 45 flat surface.

Figure 11 is a sectional view on line C—C of Figure 1, showing one side of the tower.

Figure 12 shows one of the several pinnacles 7, 8, 9 etc. on a larger scale.

Figure 13 is a sectional view taken substantially on the line 13—13 of Figure 12.

Referring to the drawing of the invention more in detail.

Figure 1 shows elevation of upper portion of a 55 church tower with its pilaster columns 1 and

shows their return corners 2 and the dark glass trim 3 that is extended outward and the recess in the windows and their trim and the return on the pilaster 1 are for the purpose of pulling out the pilaster columns their full length for appearance. The recessed windows in the recesses 20 of the pilaster columns comprising a tower body formation are purposely not tied together with a belt at their tops at 5. Above 5 the pedestal 6 is recessed back considerably from the face of pinnacles 7 terminating in pyramidions. These pinnacles 7 are the topping off of the pilaster columns and the starting of a group of pyramidions so placed that they eliminate the fault of the large noticeable offsets as the tower is tapered off. This is a thing that architects have tried to do for the last thousands years. The other thing this design accomplishes is that it ties the whole tapered top comprising a surmounting tower zone into the main structure by making each upper tier of pinnacles a little smaller than the ones just under them, but preferably makes all of the same general design, but of the same general design as tops of pilaster columns, and 7, 8, 9, 10, 11, 12 and 13 are all evenly spaced to make an even taper in appearance as shown by line 67, and each of the pyramidions is smaller nearing the top. On the extreme top of pinnacles is placed a cross 14 and on the lower portion of the symmetrical tapered top there are three crosses 15, symbols of the Trinity. All crosses are illuminated in daylight when the sun shines on them and give the resemblance of large diamonds. These crosses are illuminated at night by floodlights 16 which may be easily gotten to by doors 17 opening inward. Obviously the upper tiers of pinnacles are supported on suitable offset portions of the tower but the pyramidion top portions of successively reduced size serve effectively to conceal and disguise such offsetting.

The upper cross 14 may be illuminated at night by floodlights 16 and may be serviced through doors 19. The pilaster columns 1 are tapered at each outside edge and returned at 2 to cause a recess at 20 to make each column stand out as an individual unit and not tied together at the top with the usual belt. This is done to clearly bring out each as a column its full length. The tower is built its full length to seem as one complete unit all tied together for one purpose, to support the cross on top with dignity and reverence with its many points pointing upwards toward Heaven.

One form of constructing the cross 14 is as shown in Figure 2; an upright pipe 21 and the arms extending out about horizontally as indicated at 22 and threaded at 23. The reflectors as shown at 24 and 25 etc. are made of truncated sphere-shaped hollow glass and their inside surfaces silvered like a mirror to reflect the sun. The curve allows these flashes 25-A of sunbeam to flash in many directions. The sunbeams hit the reflectors and cast flashes in the directions of 26, 27 and 28 equally beautifully, and in many other directions not indicated. It is equally true of all the other reflectors and these several reflectors give the appearance of a great flaming cross, and the brighter the sun shines the brighter the cross seems by sun illumination. The reflector 29 is put on in half sections and held together by screws at 30, and then rubber ring 31 slipped over the pipe 22 as a cushion and seal between reflector 29 and reflector 32. The cushion ring 31 as shown in Fig-

ure 6 and Figure 7 has an extension 33 to keep the reflector from touching the pipe 21 and 22 to keep 24 and 25 from breaking by vibration, and also as seal so the ventilation may be governed through the pipes 21 and 22 through holes 34 in the pipe into the reflectors and by desired size hole in caps at 35 and other inlets held to equalize temperature inside to that outside and eliminate sweating.

Figure 3 shows a section view of one of the reflectors taken at line A—A. 36 shows the glass thickness and shape and 37 is a section of the pipe. 38 is silvering and its protector on inside of the truncated sphere reflector.

Figure 4 shows one end of a reflector 32 and a section of the pipe the reflector slips over.

Figure 5 shows an enlarged side view of a truncated sphere reflector and Figure 7 shows an edge view of the rubber washer 31 placed between the reflectors to protect them from breakage and to seal the ends of the reflectors. The extensions 33 keep the glass from touching the pipes 21 and 22 eliminates breaking as well as making the connections air tight and air circulation through the reflectors regulated by holes in pipes 34 and 35 and holes in reflectors at 39 for moisture change and draining. Figure 6 is just a side view of washers as in Figure 7.

Figure 8 shows an end view of a reflector, the shape of which may be desirable where the cross is located in certain locations relative to the altitude of surrounding country to that of the altitude of the location of the cross, and also where it is desirable to get effect of the reflection of the sun where the cross is between eyes looking at the sun rays in the general direction of the sun arrows 39—A and are reflected to reflect sun on opposite side from the sun as indicated at 40. The radial point in making curve is longer radius as at 41 and the shorter radius at 42 on ends same as the whole reflector used in cross in Figure 2.

Figure 9, the reflector 43 is about a half of the truncated sphere in Figure 5 and as indicated at 43 used on crosses or the like and may be used on a flat support as at 44 and may be fastened by means of screw 45 and may be preferable in the three crosses 15.

Figure 10 shows a reflector 46 with a reverse curve as at 47 which may be desirable in some situations but serves to reflect sun or artificial rays of light to certain locations relative to the reflector.

Figure 11 shows a cross section of small portion of the main tower at line C—C in Figure 1, and shows the desired deep recess on each edge of the pilaster columns 1 at 20 where the relief structure or window trim are set back and the return 2 on pilaster column serves as bringing out the pilaster columns 1 boldly, and the windows and trim 48 are dark and bring out the light colored long columns their full length.

The reflected sun rays off of the cross 14 cover quite a territory, sun rays coming in at directions as at 49 and leaving the reflector as at 50 and 51, and at night when the crosses are illuminated by floodlights 16 and 18 the flash covers a variety of angles also. The cross 14 floodlighted by lights 18 by rays indicated at 18—A, and crosses 15 at the bottom floodlighted by lights 16 and as indicated by rays 16—A.

Figure 12 is an enlarged elevation of one of the pinnacles 7, 8, 9, etc. The face A—1 is a broad view and its corners 2—A are returned on 45-degree angle. The tops of portion of 2—A are cut

at a steep angle to a point at 2-B to give a pointed Gothic appearance. The flat face A-1 is stopped on the horizontal at 56 for contrast, and the plain relief arrow pointed relief posts 53 run quite a distance below the top 56 on the flat surface at 53-A and also quite a distance above and pointed at 53-B to give a very pointed Gothic effect to the completed pinnacle, and the many points pointing toward Heaven is symbolic of the One now in glory who once hung on the cross, and the completed tower of many pinnacles points Heavenward and general direction of the cross and lattice strips 54 are supporting the pointed relief posts 53 at quite a little off the horizontal as a relief work and to support and emphasize the sharp pointed relief posts 53. All this is to work together to complete a symmetrical tapered tower to a peak to support the cross 14.

at line 13-13. The steeple 61, or the four pointed at line B-13. The steeple 61, or the four pointed portions of the pinnacles has a square base 62 and taper to a point 63.

The thing new and novel in the combination of pinnacles 8 to 13 and 61 and shown in detail in Figure 12 is the distance is greater from the faces 64 to 64-A than it is from face 65 to face 65-A and allows space to use post 66 back of the pointed part of 2-A, which makes a well planned place to stop the lattice 54 and 15 above the horizontal line 56. This allows a support for ends of lattice 54 and these lattices give the effect of strengthening the pointed relief post 53 and contrast for the many vertical lines.

The main idea of the seven tiers of pinnacles to taper top of tower is to avoid irregularity in offsets and finish the tower to a point with the different top points and point of one relief post of each pinnacle about touching the line 67. As shown 68, 69 and 70 and all other points on the outside of the different pinnacles that are placed on the four corners about touching the line 67 and thus overcoming the obstacle that has confronted architects for years. This specially designed pinnacle overcomes difficulty of objectionable offsets of church tops and makes a beautiful top that looks as if made for the purpose of supporting the cross, and persons seeing any portion of this tower from a distance from top to bottom it immediately causes person seeing it to know they are looking at part of a church tower. Eliminating noticeable offsets in church towers may be accomplished by other style pinnacles or ornaments by setting the outside of upper tier overlapping the inside part of lower tier.

The idea of daylight illumination by sun rays or at night by full moon or by artificial light may also be used for signs to be seen at a long distance. The sun ray reflection differs to that of any artificial light rays as the rays of artificial rays waste and soon dim out, but sun rays travelling millions of miles before reaching reflector may be reflected by mirror reflectors a great distance through darkness and are practically as bright at a great distance as close up. So the sunlight reflections may be seen at long distances.

It is strictly understood that changes may be made within the scope of the drawing and claims without departing from the spirit of the invention.

5 What I claim as new and novel is:

1. In architectural tower structures adapted for use with edifices purposed for religious activities, a tower body formation of generally rectangular shape in plan view, a surmounting assemblage 10 rising from the body portion and comprising a plurality of individual pinnacles each terminating in a pyramidion with the pinnacles arranged in a rising step formation on each side, and with the vertices of the pyramidions of each step located successively inwardly to form a composite pyramidal structure to thereby present a sky-line pseudo-pyramidal appearance of the surmounting tower assemblage and eliminate the appearance of offset formations lying outside of the 15 pseudo-pyramidal contour, the pinnacles of adjacent predetermined steps varying as to number with other adjacent predetermined steps presenting a similar number of pinnacles but varied in spacing width to thereby produce the pseudo-pyramidal contour, and a cross formation carried by and rising from the vertex of said surmounting assemblage.

20 2. An assemblage as in claim 1 characterized in that the tower body is formed of a plurality of vertically extending structural formations on predetermined side faces of the tower, each of such faces having its formations in side contact and with the exposed formations of a face arranged to present collectively two distinctive appearance 25 types arranged in alternation, each type extending continuously lengthwise of the tower body to thereby present a horizontal series of vertically extending bands with adjacent contacting bands formed from different types and with alternate bands formed of the same type, the pinnacles of the lower step of the surmounting assemblage of such face being positioned to surmount the bands of but one of the types to thereby continue the spacing of the bands of the other type into such 30 35 40 45 surmounting assemblage.
